UNITED STATES PATENT OFFICE.

JOSEPH N. TOMES, OF CLEAN, NEW YORK, ASSIGNOR TO J. N. TOMES SMOKE CONSUMER AND FUEL ECONOMIZER CO., INC., OF BUFFALO, NEW YORK, A CORPORATION OF NEW YORK.

SMOKE CONSUMER.

Application filed September 19, 1919. Serial No. 324,866.

To all whom it may concern:

Be it known that I, JOSEPH N. TOMES, a citizen of the United States, residing at Olean, in the county of Cattaraugus and State of New York, have invented certain new and useful Improvements in Smoke Consumers; and I do hereby declare the following to be a full, clear, and exact description of the invention, such as will enable others skilled in the art to which it appertains to make and use the same.

This invention relates to smoke consumers, and more particularly to a smoke consumer for use in connection with furnaces by means of which the smoke and other products of combustion are conducted through the furnace grate so as to be burned thus effecting a material saving in fuel.

One of the main objects of the invention is to provide a smoke consumer of simple and inexpensive construction which may be readily applied to furnaces of standard construction.

A further object is to provide a smoke consumer which may be operated, after once started, by steam generated within the boiler of the furnace.

Further objects will appear from the detailed description.

30 In the drawings:

Figure 1 is a front view of a furnace of standard construction with a smoke consumer constructed in accordance with my invention applied.

35 Figure 2 is a back view.

Figure 3 is a central vertical longitudinal section through the furnace showing the smoke consumer applied, parts being shown in section in this view.

40 As illustrated, the smoke consumer is applied to a furnace of standard construction including a casing A within which is supported the boiler B and grate C beneath the boiler, the inner end of this grate being supported by the usual fire wall D. The boiler is of tubular construction being provided with the longitudinally extending spaced flue tubes E of known type, these tubes communicating at their forward ends

50 with a smoke box F which communicates at its top with a stack G provided with a suitable valve or damper 1. The products of combustion from the fire box flow rearwardly over the fire wall D through the space H

and upwardly into the rearward ends of the 55 flue tubes.

A smoke return pipe 2 communicates at its upper end with the smoke box F below the damper 1, this pipe communicating at its lower end with the ash pit adjacent the forward end thereof, beneath the grate C, as in Figure 3. A fan 3 of suitable type is mounted at the rear of the furnace, the shaft of this fan being provided with a pulley 4 secured thereon by means of which the fan 5 may be readily connected to a motor for operating the same. This fan is provided with an intake pipe 5 and a discharge pipe 6, the discharge pipe communicating at its upper end with a header box or casing 7 mounted at the central portion of the back of the furnace casing A. A plurality of inwardly extending tubes 8 communicate with the header casing 7 at their outer ends, these tubes projecting into the upper portion of space H and being disposed in alignment with and adjacent to flue tubes E of the boiler. A steam supply pipe 9 communicates with the casing 7 at the top thereof, this pipe being connected to the steam dome B' of the boiler B and provided with a suitable control valve 10. The flow of air from fan 3 into casing 7 is controlled by a damper 11 in the fan outlet pipe 6.

In practice, when first starting the furnace, the valve 10 is closed, valve 11 being open, and the fan 4 is operated through the medium of an electric motor or in any other suitable manner so as to force air into the header casing 7 through pipe 6. 85 The damper 1 of stack G is so adjusted as to cause the products of combustion flowing into the smoke box F to flow into the upper end of the return pipe 2, from which they are discharged into the ash pit at a point beneath the grate C. The air which is in the header casing 7 under pressure is discharged through the tubes 8 at high velocity, this air flowing through the flue tubes E of the boiler and serving to create a partial vacuum within the upper portion of space H thus inducing a current of air and the products of combustion which have been returned to the ash pit by the return pipe 2 to flow upwardly through the grate C and the fire supported thereby. This mixture of air and smoke which is generated upon first starting the furnace is 90 95 100 105

thus caused to flow through the fire supported by the grate so as to be consumed thereby. It is apparent that the tubes 8 become heated to a great degree, during 5 operation of the apparatus. As the smoke generated during operation of the furnace is composed to a great extent of gases the same may be burned, thus effecting a material saving in fuel while also preventing 10 the escape of smoke into the atmosphere. After the apparatus has been in operation for a short time so that steam is generated within the boiler B at the desired pressure, the fan 3 may be stopped, 15 after which the damper or valve 11 of pipe 6 is closed, valve 10 of the steam pipe being open so as to admit steam under pressure into the header casing 7. This steam is injected by the heated injector tube, at high 20 velocity and in a small, fine spray into the flue tubes E and acts in the same manner as the air in the operation previously described to induce flow of the products of combustion through the return pipe 2 and grate C. 25 This steam mixing with the products of combustion and then passing through the fire supported by the grate C is, under the influence of the high temperature of the fire.

30 I have found by experience that the

damper 1 may be readily adjusted so as to insure complete combustion or burning of the combustible ingredients of the products of combustion from the furnace, thus effectually preventing escape of smoke into 35 the atmosphere while also utilizing these combustible products for heating the boiler B.

What I claim is:

In combination with a furnace including 40 a boiler, a smoke box in communication with the firebox and the ashpit, means operable to close the smoke box whereby the smoke will be discharged into said ashpit, a header, tubes extending from the header 45 and terminating short of and relatively close to the tubes of the boiler, a fan in communication with said header, a steam supply pipe in communication with said header and the steam zone of the boiler, and valves operable independently of each other to cut off the supply of air or steam to said header.

In testimony whereof I affix my signature in presence of two witnesses.

JOSEPH N. TOMES.
